Inventor:

Garthorne F. Corbett

CATHARINE F. CORBETT, OF BOSTON, MASSACHUSETTS.

Letters Patent No. 89,028, dated April 20, 1869.

IMPROVEMENT IN FLUTING-MACHINES.

The Schedule referred to in these Letters Patent and making part of the same.

To all whom it may concern:

Be it known that I, CATHARINE F. CORBETT, of Boston, in the county of Suffolk, and State of Massachusetts, have invented certain new and useful Improvements in Fluting-Machines; and I do hereby declare that the following is a full and exact description thereof, reference being had to the accompanying drawings, and to the letters of reference marked thereon.

To enable others skilled in the art to make and use my invention, I will proceed to describe its nature, construction, and use.

The nature of my invention consists in hinging to a suitable base-board a series of small rods, and in combining with the same, by means of overreaching arms, a longitudinal pressure-bar, for the purpose of holding the ends of the rods in position.

Drawings.

Figure 1 is a perspective view of my machine, showing all the rods down, but indicating, by dotted lines, their appearance when raised up.

Figure 2 is a longitudinal section of my machine.

Figure 3 is a cross-section of the same.

I construct my machine as follows:

A B, in all the drawings, represents the base, which may be of any suitable size.

H H H, &c., are small rods, hinged at K, as shown in fig. 3.

The hinge K may be constructed as indicated, that

is, by simply passing a small wire through the ends of the rods, or each rod may be provided with an ordinary hinge.

C C' and D D' are projecting arms, attached to each end of the board, as shown in fig. 1, one C C', of which serves to hold the end E, of the pressure-bar E F, said bar being attached by the hinge L. The other end, F, of the bar, is held down by the button G, fig. 1.

To use my machine, I proceed as follows:

The bar E F is turned up, as represented by the dotted lines E', fig. 1, then each alternate rod is turned up, and the article to be fluted is placed on the bars that were not turned up, and the alternate rods are brought down, and made fast by the bar E F.

The article to be fluted occupies the position x y, fig. 2.

To complete the operation, I have only to stiffen the article, by means of sizing and a hot iron.

What I claim as my invention, and desire to secure by Letters Patent of the United States, is—

In a fluting-machine, the combination and arrangement of the hinged rods H H H, &c., the arms C C' D D', and the pressure-bar E F, substantially as described, and for the purpose set forth.

CATHARINE F. CORBETT.
